(57) **CLAIM**

We claim the ornamental design for a headlamp with autodimming feature, as shown and described.

DESCRIPTION

FIG. 1 is a front perspective view of a headlamp with autodimming feature of the present disclosure;

FIG. 2 is a front elevational view of the headlamp with autodimming feature of FIG. 1;

FIG. 3 is a top elevational view of the headlamp with autodimming feature of FIG. 1;

FIG. 4 is a first side elevational view of the headlamp with autodimming feature of FIG. 1;

FIG. 5 is a second side elevational view of the headlamp with autodimming feature of FIG. 1;

FIG. 6 is a top plan view of the headlamp with autodimming feature of FIG. 1; and,

FIG. 7 is a bottom plan view of the headlamp with autodimming feature of FIG. 1.

Broken lines are environmental only and form no part of the claimed design.
